FOREIGN PATENT DOCUMENTS

CN 309126995 * 2/2025

Primary Examiner — Messina L Smith*Assistant Examiner* — Carolyn W Davis(74) *Attorney, Agent, or Firm* — Nicholas Makridakis(57) **CLAIM**

The ornamental design for a fan for engine, as shown and described.

DESCRIPTION

FIG. 1 is a perspective view of a fan for engine showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the fan for engine that form no part of the claimed design.
